UNITED STATES PATENT OFFICE.

ELIAS EARLE, OF TOWNSVILLE, SOUTH CAROLINA.

CORKSCREW.

1,036,980.

Specification of Letters Patent. Patented Aug. 27, 1912.

Application filed February 27, 1912. Serial No. 680,277.

To all whom it may concern:

Be it known that I, ELIAS EARLE, a citizen of the United States, and a resident of Townsville, county of Anderson, and State 5 of South Carolina, have invented certain new and useful Improvements in Corkscrews, of which the following is a specification.

My invention is an improvement in cork-screws, and has for its object the provision of a simple, inexpensive, easily operated device of the character specified, especially designed to prevent the screw from slipping or pulling out of the cork, or the pulling 15 off of the top of the cork, leaving the inner end of the cork in the bottle.

In the drawings: Figure 1 is a front view of the improvement, with the parts in one position; Fig. 2 is a similar view, with the 20 parts in another position; and, Fig. 3 is a section on the line 3—3 of Fig. 2.

In the present embodiment of the invention, the cork-screw consists of two similar sections pivoted together intermediate their 25 ends and provided with a spring between the sections, for a purpose to be described. Each of the sections consists of a handle portion 1 and an integral screw portion 2, and each of the handle portions is plane on 30 its inner face, and is rounded on its outer face, in such manner, that when the handle portions of the two sections have their plane surfaces in contact, the handle is approximately circular in cross section.

The handle as a whole, that is the two 35 portions 1, tapers toward each end, to afford a convenient grip, and at the junction of the handle and screw portion, each section has a pair of inwardly extending laterally spaced lugs 3. The lugs of one section 40 are somewhat nearer together than the lugs of the other section, so the said first named lugs will fit between the second named lugs, and the lugs have registering perforations 45 for receiving a pivot pin 4, which is headed at each end, as shown at 5, to prevent removal of the pin. The screw portions 2 of the sections are so arranged that when the 50 said portions are in the position of Fig. 1, a complete screw is formed. The screw portion of each section has a plane inner face, so that the said faces fit smoothly together, and when so arranged, the vane or blade 5 of the screw is continuous, and extends to 55 the lower end of the tool. One or both of the sections has the handle portion arranged

at a slight angle to the screw portion, so that when the screw portions are together, as shown in Fig. 1, the handle portions are separated, at the end remote from the pivot 60 pin 4, and when the handle portions are together, the screw portions incline away from each other toward their free ends. The latter position is shown in Fig. 2, and the former, which is the normal position, is 65 shown in Fig. 1. The sections are held in the position of Fig. 1 normally, by means of a spring. The said spring is formed from a wire or rod of resilient material, of suitable cross section, doubled upon itself, 70 and then bent to form a coil 7, intermediate the ends of the doubled wire, for encircling the pin 4, and two arms 8, for engaging the handle portion 1. Each arm 8 extends longitudinally of the inner plane face of a 75 handle portion, and the said face is preferably recessed to receive the arm, so that the arm is flush with the said surface, to permit the portions to fit smoothly together.

As is known when the usual form of cork 80 screw is turned into a cork, and traction is made on the handle, the screw frequently pulls out of the cork and leaves it in such shape, that the screw cannot again secure a grip. Again the outer end of the cork may 85 be broken away from the inner end. The improved screw is introduced in the usual manner, and the mere act of gripping the handle to secure a good grip for exerting traction, presses the handle portions together, and spreads the screw portions, so 90 that the screw as a whole is approximately cone shaped, with the small end upward, and cannot by any possible chance pull out of the cork. When so spread or extended 95 the screw cannot slip, and the cork must come out when sufficient traction is exerted on the handle. The handle portions in the position of Fig. 1, offer a good grip for turning the same, while in the position of Fig. 2, they offer a good grip for traction. The device is in fact a cork screw of ordinary form split longitudinally into two similar sections, pivoted together at the junction of handle and screw, and bent as 100 described.

I claim:

1. A cork screw, comprising two similar sections, each consisting of a handle portion and a screw portion, the meeting faces of the 110 said portions of the sections being plane and fitting smoothly together, to form a rounded

handle at one end of the sections and a continuous screw at the other, the handle portion of each section being bent outward at a slight angle to the screw portion, a pivotal connection between the sections at the junction of the handle and screw portions, and a spring between the handle portions of the sections.

2. A cork screw divided longitudinally into two similar sections, each section comprising a handle portion and a screw portion, the handle portion of each section being inclined outwardly toward the end remote from the screw portions, a pivotal connection between the sections at the junction of the handle and screw portions, and a spring between the handle portions of the sections pressing said sections away from each other.

3. A cork screw divided longitudinally into two similar sections, each section comprising a handle portion and a screw por-

tion, the handle portion of each section being inclined outwardly toward the end remote from the screw portion, a pivotal connection between the sections, and a spring pressing the screw portions of the sections together.

4. A cork screw divided longitudinally into two similar sections, each section comprising a handle portion and a screw portion, the handle portion of each section being inclined outwardly toward the end remote from the screw portion, and a pivotal connection between the sections.

5. A cork screw divided longitudinally into two similar sections, each section comprising a handle portion and a screw portion, and a pivotal connection between the sections.

ELIAS EARLE.
